UNITED STATES PATENT OFFICE.

HENRY W. LAMP, OF MADISON, WISCONSIN.

CLOTHES-DRIER.

No. 904,970.

Specification of Letters Patent.

Patented Nov. 24, 1908.

Application filed March 31, 1908. Serial No. 424,408.

To all whom it may concern:

Be it known that I, HENRY W. LAMP, a citizen of the United States, residing at Madison, in the county of Dane and State 5 of Wisconsin, have invented a new and useful Clothes-Drier, of which the following is a specification.

This invention relates to clothes driers, and has for its object to provide a new and 10 improved clothes drier which is adapted to be used where room is to be economized, as, for example, in connection with piazzas in flats and tenement houses, or to be placed against the walls of buildings or other suitable out of doors support.

To this end the invention consists of a clothes drier provided with extensible supporting members adapted to carry a number of clothes lines or other clothes supporting 20 means.

Referring to the accompanying drawings:—Figure 1 is a plan view showing a clothes drier constructed in accordance with this invention, with the extensible members 25 broken away. Fig. 2 is a side view of the device shown in Fig. 1: Fig. 3 is a detail view of a portion of the clothes drier showing one of the extensible supporting members folded up.

Similar numerals of reference are employed to indicate corresponding parts throughout the several figures of the drawings.

To a wall or other suitable support are secured two brackets 1 which may be arranged at the opposite sides of a window. Each bracket comprises a base plate 2 having a pair of horizontal arms 3 disposed near the lower end of the base and an upper arm 4 arranged near the top of the base.

The brackets are preferably formed of cast metal and the outer ends of the arms 3 are bored for the reception of a pair of blocks 8 of steel or brass, and these are arranged to receive the end portions of the hub of a worm wheel 7 said hub being provided with a centrally disposed threaded opening. Intermeshing with each worm wheel is a worm 9, the worms being mounted on a shaft 10 that is mounted in bearings formed in arms 11 projecting from the base, and at one end of the shaft is a handled operating crank 12.

The threaded openings in the worm wheels 55 7 receive threaded rods 12' which are raised or lowered in accordance with the direction

of rotation of the worm wheels. The upper ends of the rods are of rectangular or other noncircular form in cross section and extend through similar shaped openings formed in 60 the upper portions of the stationary arms 4.

On each bracket is mounted a series of pivoted levers arranged in the form of lazy-tongs 14 one end member 15 being pivoted to the arm 4 the other end member 16 being 65 pivoted to the vertically slideable bar 12' so that as the latter is moved upward the lazy-tongs will be extended and when removed downward the lazy-tongs will be contracted.

Each of the pivot pins at the intersection 70 of the crossing links that constitute the lazy-tongs is provided with an inwardly extending lug 17 having an opening for the passage of a clothes-line so that the clothes to be dried may be hung on these lines and the 75 lazy-tongs extended in order to project the clothes outward from the wall or other support. The two lazy-tongs are connected to each other and braced by a small cross bar 19.

In order to protect the device a suitable hood 20 is employed. The upper end of the hood is secured to the top of the brackets 1 and at its outer end is hinged a flap 21 which may be raised by a line 22 extending over a 80 pair of guide sheaves 23 and 25. The guide sheave 23 is carried by an arm 24 projecting from one of the brackets, and when the line is drawn inward for the purpose of raising the flap to the position shown in Fig. 2 its 85 end may be secured to a suitable hook or cleat 28 secured to one of the brackets.

I claim:—

1. In combination, a pair of spaced supporting brackets, vertically movable rods 95 guided therein, means for operating said rods, and lazy-tongs having their inner ends connected to the brackets and rods.

2. In a clothes drier, a pair of supporting brackets, a pair of lazy-tongs, pivot lugs 100 forming the connections between the members of the lazy tongs and serving also for the reception of a clothes-line, and mechanism carried by the brackets for simultaneously actuating the lazy-tongs.

3. In a clothes drier, a pair of brackets each having a plurality of projecting arms, vertically movable rods guided by said arms and provided with threaded portions, worm wheels having threaded openings for the reception of the threaded portions of the rods, worms engaging said worm wheels, an oper- 110

ating shaft carrying the worms, and a pair of lazy-tongs the members of which are connected to the bracket arms and the rods whereby on movement of the rods the lazy-tongs may be extended or contracted.

4. In clothes drier, a pair of spaced brackets having projecting arms, vertically movable threaded rods guided by said arms, worm wheels having threaded openings for 10 the reception of the rods, worms engaging the worm wheels, a shaft carrying said worms, a pair of lazy-tongs having their ends connected to the arms and rods whereby

the lazy-tongs may be extended or contracted, clothes-line attaching lugs carried by 15 and forming the pivotal connections of the lazy-tongs members, and a cross brace extending between the said lazy-tongs.

In testimony that I claim the foregoing as my own, I have hereto affixed my signature 20 in the presence of two witnesses.

HENRY W. LAMP.
